UNITED STATES PATENT OFFICE.

AARON CHARNEY, OF CHICAGO, ILLINOIS.

DUSTER MOP AND POLISHER.

Application filed April 15, 1927. Serial No. 183,934.

This invention relates to improvements in mitt-type mops, dusters and the like, and more particularly to a duster or polisher adapted to be slipped over the hand of the user, and which is more efficient in its operation and which may be manufactured at materially less labor and cost than devices of this character now in use.

Devices of similar nature now in use and heretofore known are usually formed by sewing a plurality of individual strips, of shortened strands of soft twine or the like, on the bottom piece of a hand pouch so that they are parallel to the fingers of a human hand. These strips are usually provided with a binder or hem and, obviously, the sewing of each individual strip is a separate and distinct operation, thereby making the production cost objectionably high. Moreover, parts of these strips frequently become loose, and the strips do not cover the lower surface of the device as well as may be desired, but tend to part and leave bare portions of the hand pouch exposed.

With these objections in view it is accordingly an object of this invention to provide a mop or duster adapted to slip over the hand of a user and to which the mop fabric itself is secured in a single operation.

Another object of this invention is to provide a hand mop or polisher, the mop fabric of which completely and effectively covers the entire under surface of the body of the device.

A further object of this invention is to provide a hand covering duster or polisher which is strong and durable, and which may be very economically manufactured.

Other and further important objects of this invention will be apparent from the disclosures in the specification and accompanying drawings.

This invention (in a preferred form) is illustrated in the drawings and hereinafter more fully described.

On the drawings:

Figure 1 is a top plan view of a device embodying features of this invention.

Figure 2 is a view similar to Figure 1 with parts broken away.

Figure 3 is a vertical sectional view taken substantially along line III—III of Figure 2.

Figure 4 is a bottom plan view of the device.

As shown on the drawings: In the illustrated embodiment of this invention there is shown a hand pouch or mitt 1 formed of the top piece 2 and bottom piece 3 secured together by stitching as shown at 4, leaving an entrance opening for the insertion of the hand of the user, adjacent which opening the usual flexible wrist band 5 is provided. The top piece 2 and the bottom piece 3 may be made of any desirable material but are preferably of light-weight fleece-lined canvas which may be made water or moisture proof if desired to permit use of an oiled mop portion.

A mop fabric 6 composed of any desirable material or as shown of shortened strands of soft twine, is secured to the under side of the lower piece 3 by stitching 7. A hem or binder, of course, may be used on the mop fabric adjacent the piece 3 if so desired, but it is entirely unnecessary to the durability or proper functioning of the present invention. It is to be noted that the mop fabric 6 is secured to the lower piece 3 by substantially spiral stitching 7 whereby the entire mop fabric 6 is secured to the lower piece 3 of the hand pouch 1 in one single and continuous operation. It is also to be noted that, due to this novel means of securing the mop fabric to the pouch, very few convolutions in the seam are needed, the convolutions having relatively wide spaces therebetween, and yet the fabric will completely and effectively cover the entire under surface of the pouch as shown in Figure 4 and will not tend to separate along each securing seam and thereby expose bare portions of the pouch itself.

In making the present invention the lower portion 3 of the hand pouch or mitt is cut to any desired size and the mop fabric is sewn directly thereto in a single and easy operation, forming a substantially spiral seam 7. The top portion 2 of the pouch is then sewn to the lower portion 3 as shown at 4, after which the flexible wrist band 5 is sewn to both pouch portions 2 and 3 so as to circumscribe the entrance opening.

By making the mitt or pouch of constantly increasing width from the wrist portion to substantially the tip portion thereof the

device is made more comfortable due to the free action permitted to an operator's fingers and at the same time a larger effective dusting area is provided.

5 It will be observed, by reference to the drawings, that the plan outline of the mitt is spatular in form, being wider near the closed end, and, as stated, of sufficient width to accommodate the hand when the thumb 10 and fingers are fully extended, thereby to cover more area of the surface acted upon by the mitt and to place the digits of the hand in positions to render most effective work without cramp or fatigue.

15 From the foregoing, it is readily apparent that I have provided a hand mop, duster, or the like which is durable and efficient, which obviously has decided advantages over any known devices of this character, 20 and which minimizes the labor and cost of production.

I am aware that many changes may be made and numerous details of construction 25 may be varied through a wide range without departing from the principles of this invention.

tion and I, therefore, do not purpose limiting the patent granted hereon, otherwise than necessitated by the prior art.

I claim as my invention:

1. In a device of the character described, a 30 spatulate hand pouch, and a mop fabric comprising a plurality of strands of fibrous material secured to the under face of said pouch by a single and continuous curvilinear seam, whereby said fabric will at all times completely cover that portion of said pouch to which said fabric is secured. 35

2. In a device of the character described, a hand pouch, and mop strands secured to the palm portion of said pouch by a spiral seam forming spaced convolutions, whereby said strands will commingle so as to give the effect of a solid matted surface leaving none of said palm portion exposed in the region of said fabric. 40

45 In testimony whereof I have hereunto subscribed my name at Chicago, Cook County, Illinois.

AARON CHARNEY.
